UNITED STATES PATENT OFFICE.

ARTHUR PAULSON, OF NEW YORK, N. Y., ASSIGNOR TO CHRISTIAN IVERSON, INC., OF NEW YORK, N. Y.

FILING DEVICE.

Application filed October 14, 1927. Serial No. 226,101.

My invention relates to improvements in filing devices, and more particularly to that class such as are made of cardboard, which are low in cost to manufacture. An object 5 of my improvement is to produce such an article but which will in addition be so constructed as to provide all the modern features of design which are present in more expensive files in response to the fastidious demands of the market, such files being usually of an all metal character. Other objects include ease of access to the contents of the file, the absence of bolts or rivets to minimize labor costs, compactness, rigidity and 15 neat appearance.

With this in view I attain these objects by the mechanism illustrated in the accompanying drawings forming a part of this specification in which like reference characters refer to like parts throughout the various figures, and in which,

Fig. 1 is a perspective view of my improved filing device with the cover shown raised and the front extension member 25 shown in an extended position.

Fig. 2 is a plan view with the extension member closed.

Fig. 3 is a vertical section on the line 3—3 of Fig. 2.

Fig. 4 is a section on the line 4—4 of Fig. 3.

Figs. 5, 6, 7 and 8 are perspective views of the several component parts. Fig. 8 illustrating more particularly the part shown in Fig. 7 after it has been properly bent for insertion in the final step of assembly.

Referring to the drawings for a more detail description, the improved filing device consists of a body portion A, preferably 40 made of heavy cardboard, comprising a back panel 2 and ends 3 and 4 which latter are bent at right angles so that the whole will snugly engage the three sides of a rectangular bottom panel 5, preferably made of wood of a suitable character. Body portion 45 A may be secured to panel 5 by nails 6 as clearly shown in Fig. 5.

A front extension member is indicated at B and is shown in Fig. 6 prior to the bending of the guide ends 7 and 8, which subsequently appear as in Fig. 1, the panel 9 forming the front of the extension. To strengthen the panel 9 as well as for other purposes presently to appear, an additional 55 panel 10 is securely glued to its inner sur-

face and extends slightly above the upper edge thereof, as at 11, to provide an overlapping engagement with a cover C when the latter is closed and thereby prevents the extension B from accidentally opening. The 60 ends 7 and 8 are apertured at 7^a and provided with a tooth 7^b on their respective top edges for a purpose to be subsequently explained.

The cover C includes a substantially continuous downwardly projecting flange 13 forming a box-like rectangular structure. A hinge for the cover is shown at 14 and may be a strip of fabric glued to the rear flange 65 of the cover and to the panel 2 as shown in Fig. 3.

It will be understood that the parts of the file may be covered with leather, figured paper, fabric or any other suitable material which will add to their appearance and 70 hide hinges, nails or other unsightly features but which forms no part of this invention and has not been shown in the drawings other than a general indication in Figures 1 and 2.

Hinges for extension B include two strips 15 similar to strip 14, which may be glued between panels 9 and 10 along one edge, and to bottom panel 5 along the opposite edge 75 respectively. A reinforcing hinge tab 16 is 80 also attached as shown in Fig. 3, providing a very substantial construction.

In Figures 7 and 8 is shown what may be termed a lining member D consisting of three panels when bent, as in Figure 8, to form end 85 panels 17 and 18 and a bottom panel 19. Member D serves the dual purpose of providing double walls at the sides and bottom of body portion A when inserted therein, and spaces for the insertion of ends 7 and 8 90 of extension B including suitable stops to limit the extent of the movement of said extension.

These stops consist of triangular spacing blocks 20 and 21 which are glued to the outer 100 surfaces of the end panels 17 and 18 of member D, and additional spacing blocks 22 and 23 secured thereto in the same manner. Both sets of blocks are attached when member D is in the position shown in Fig. 7, a coating 105 of glue being also applied to their outer surface as indicated at 24 in Fig. 8 the purpose of which will presently appear.

Referring to Figures 5 to 8, these various parts are assembled as follows: The guide 110

ends 7 and 8 are bent upwardly from the position shown in Figure 6 and are inserted in the body portion A in snug engagement with the ends 3 and 4. Hinges 15 are then glued to 5 the top surface of the panel 5 and the tab 16 is bent around the front edge and beneath panel 5 and firmly glued thereto as shown in Figure 3. Member D is now ready for insertion. It is bent into the shape shown in Figure 8, 10 lifted by grasping the end panels 17 and 18, and placed in position within the body portion A, the bottom panel 19 resting upon panel 5. The end panels 17 and 18 are somewhat inclined towards each other during this operation so that the spacing blocks 20 and 21 15 can be pushed into the apertures 7^a of the guide ends 7 and 8, whereupon end panels 17 and 18 are pressed outwardly so that the glued surfaces 24 will contact with the inner 20 surfaces of the ends 3 and 4 to be firmly attached thereto, the whole forming an interlocking arrangement permitting the extension to be rocked outwardly on its hinges until the walls of the apertures 7^a contact with 25 the spacing blocks 20 and 21 as indicated in dotted lines in Figure 3, a tooth 25 on each of the blocks 22 and 23 being adapted to thereupon also engage the teeth 7^b as additional means for limiting the said movement. 30 When extension B is closed the blocks 20 and 21 will be engaged again by other walls of apertures 7^a as shown in full lines in Figure 3, providing greater rigidity when the parts are so positioned.

35 It will be noted that when member D is assembled within body portion A the end panels 17 and 18 will extend slightly above the top edges of the ends 3 and 4, as at 26, and corresponding in extent to that of panel 40 10 above panel 9. This feature of the construction provides inset shoulders for the cover C to rest upon when the latter is closed, as well as guiding flanges, all of which adds to the rigidity and neatness of appearance of 45 the file. Handles are provided by riveting tabs 27 to the ends 3 and 4, the rivets also piercing the end panels of the member D to more positively hold it in place. Metal angles are shown in dotted lines in Figure 2 to bind 50 the corners of cover C and which are hidden beneath the ornamental material covering the file.

55 A preferred embodiment of the invention is shown and described herein but it will be understood that there is no intention of limiting it to such details of construction, as many changes could be made without necessarily departing from the scope of the appended claims which are intended to cover all the 60 specific and generic features of the invention.

I claim:

1. A filing device comprising a body portion having three panels formed by bending a single piece of material, a bottom panel secured to said body panels, a lining member

formed in a manner similar to the body portion and adapted to fit within said body portion and form double walls for same, spacing blocks interposed between the end panels of the body and the lining member and secured thereto respectively to form spaced end walls, an extension member hinged to said bottom panel, guide ends on said extension member extending between said double walls and provisions on said guide ends adapted to engage said spacing blocks to limit the extent of the movement of the extension member. 70

2. A filing device comprising a body portion having three walls and a bottom panel, inner end panels in spaced relation to two of said walls thereby forming double walls at the ends of said body portion, blocks interposed between and secured to the inner end panels and the walls and serving to space the former from the latter, an extension member hinged to the bottom of the body portion and provided with a front panel and guide ends, the latter being adapted to extend between the said double walls and engage said spacing blocks, said guide ends having apertures 80 adapted to receive the said spacing blocks and permit the extension to swing open to a predetermined extent. 90

3. A filing device comprising a body portion having three walls and a bottom panel, inner end panels in spaced relation to two of said walls thereby forming double walls at the ends of the said body portion, blocks interposed between and secured to the inner end panels and the walls and serving to space the former from the latter, an extension member hinged to the bottom of the body portion and provided with a front panel and guide ends, the latter being adapted to extend between the said double walls and engage said spacing blocks, said guide ends having apertures 95 adapted to receive the said spacing blocks and permit the extension to swing open to a predetermined extent. 100

4. A filing device comprising a receptacle including a cover, an extension hinged to the bottom of said receptacle, said extension having guide ends bent at right angles to enter said receptacle, lining panels forming guides for said guide ends, and means for limiting the extent of the movement of said extension including blocks and apertures carried by the extension and adjacent walls of the receptacle, and adapted to engage each other subsequent to such movement. 115

5. A filing device comprising a body portion having three walls and a bottom panel, inner end panels in spaced relation to two of said walls, thereby forming double walls, blocks interposed and secured to the inner end panels and the walls and serving to space the 120

130

- former from the latter, an extension member hinged to the bottom of the body portion and provided with guide ends adapted to extend between said double walls, and means 5 to limit the extent of movement of said extension member comprising lugs on the spacing blocks and projections integral with the guide ends and adapted to engage with the said lugs.
- 10 6. A filing device comprising a body portion having three walls and a bottom panel, inner end panels in spaced relations to two of said walls, thereby forming double walls, a plurality of spacing blocks interposed be- tween and secured to each of the inner end 15 panels and its corresponding wall, certain of said spacing blocks being each formed with a lug, an extension member hinged to the bottom of the body portion and provided with guide ends adapted to extend between said double walls, and means to limit the extent 20 of movement of said extension member comprising apertures and projections on said guide ends, said apertures adapted to receive loosely certain of said spacing blocks and 25 said projections adapted to engage said lugs.

ARTHUR PAULSON.
